UNITED STATES PATENT OFFICE.

ALFRED ANDERSON, OF STROMSBURG, NEBRASKA.

TRACE-SUPPORTER.

SPECIFICATION forming part of Letters Patent No. 380,471, dated April 3, 1888.

Application filed January 26, 1888. Serial No. 261,948. (No model.)

To all whom it may concern:

Be it known that I, ALFRED ANDERSON, of Stromsburg, in the county of Polk and State of Nebraska, have invented a new and Improved Trace Supporter, of which the following is a full, clear, and exact description.

Reference is to be had to the accompanying drawings, forming a part of this specification, in which similar letters of reference indicate corresponding parts in all the figures.

Figure 1 is a perspective view of a portion of the back-pad and skirt, showing my invention applied thereto. Fig. 2 is an enlarged front elevation of the supporter, and Fig. 3 is an edge view of the same.

The invention will first be described in connection with the drawings, and then pointed out in the claims.

The trace-supporter A is attached to the back-pad skirt B, and is adjustable thereon to hold the trace T high or low, according to the size of the horse or according to the work to be done. The supporter has no direct connection to the back-pad P. It is by preference made of malleable cast-iron, with a loop, a, at the top, a tongue or projection, a', below said loop, and another loop, a'', at the lower end of the support. The passage a³ for the trace T is

D-shaped, the body of the support being formed of the plate b, slightly curved, and the curved front piece or loop, b'. The lower end of the plate b projects below the lower end of the loop b', as shown at b², and on this projection is mounted the lower loop, a''. The upper loop, a, is formed on the curve of the main loop b' and stands at an angle to the plate b, so that the support may be readily applied to the skirt B, as illustrated in Fig. 1.

Having thus fully described my invention, I claim as new and desire to secure by Letters Patent—

1. The trace-support herein shown and described, formed of the plate b, projection b², main loop b', and the upper and lower loop, a a'', the latter mounted upon the projection b², substantially as described.

2. The trace-support formed of the plate b, main loop b', projection a', and the upper and lower loops, a a'', the upper loop being set at an angle to the plate b, substantially as described.

ALFRED ANDERSON.
